UNITED STATES PATENT OFFICE

FREDERICK H. WAPPLER AND CHARLES FAYER, OF FLUSHING, NEW YORK, ASSIGNEES
TO WAPPLER ELECTRIC COMPANY, INC., A CORPORATION OF NEW YORK

X-RAY MACHINE

Application filed June 25, 1923. Serial No. 647,449.

Our invention relates to X-ray machines: that is, to machines constructed, arranged and adapted for use in connection with X-ray tubes and various parts immediately associated therewith.

More particularly stated, we seek to produce in the form of a single unit of moderate size a cabinet containing a high tension rectifying switch and a synchronous motor for actuating the switch, and also containing the X-ray tube and an X-ray tube drum, all so arranged as to develop certain advantages, as hereinafter described.

In the prior art there have been cabinets enclosing a transformer and carrying a tube drum so as to operate collectively as a unit but such a unit was not successful except when used in connection with high tension mechanism in which the currents were not rectified, or where the high tension currents were developed by means of an induction coil operated by aid of a Wehnelt interrupter.

In this connection, attention is called to the fact that where a high tension current rectifier is actuated by a motor and these parts are contained within a cabinet, the motion of the motor generally causes a considerable amount of agitation of the cabinet. Besides this, the parts mentioned as heretofore assembled were as a whole rather bulky, so that if a tube drum were added to the cabinet the unit would become too large and unwieldy for practical uses.

In the devices of the prior art the X-ray tube has not yet been made readily movable up and down to different heights or levels, and the attempts heretofore made for mounting the tube drum upon a cabinet containing a rectifier have resulted in structures which were quite clumsy, and which have been so arranged as to give too little protection to the operator and to bystanders, as against the deleterious effects of X-rays.

Our improved X-ray cabinet is so constructed and arranged so as to readily contain a transformer, a high tension rectifying switch, a motor for actuating the switch, and in addition a tube drum carrying the X-ray tube, the unit as a whole being so constructed and arranged as to enable a number of ad-

vantages to be obtained, among which are the following:

First, because of the presence of the high tension rectifying switch and the consequent fact that the currents employed are rectified, inverse discharges and immense potential strains are avoided, so that the machine is thus rendered efficient for therapy work; whereas without the features just mentioned there would be danger of producing skin burns and rendering inadequate the depth of the X-ray doses, and further, the X-ray tubes would readily become dangerously overheated, and at best would produce a much smaller percentage of useful X-rays.

Second, in our device the X-ray tube is contained in a tube drum, made up in part of metals sufficiently heavy as to render unnecessary any additional protection of this kind for the patient and the bystanders.

Third, the tube drum with the X-ray tube contained therein is movable bodily up and down, and is also revoluble upon its own longitudinal axis, so that the X-ray tube can be brought to any desired height, and the angle of the direction in which the X-rays pass out of the tube drum can be changed to direct the X-rays to any desired portion of the patient's body.

Fourth, the transformer, the high tension rectifying switch and the high tension leads to the X-ray tube are all completely housed, so that complete protection is attained as against accidental shocks from the high tension currents.

Fifth, the X-ray tube is rendered easily removable from the casing and the tube drum.

Sixth, the X-ray tube drum is provided with an opening through which the X-rays pass out, this opening being of such form and so located as to enable X-ray apertures of different sizes to be used in connection therewith, in order to facilitate the treatment of different parts of the face, mouth, neck or head of the patient.

Reference is made to the accompanying drawing forming a part of this specification and in which like reference characters indicate like parts throughout the several figures.

Figure 1 is a rear view of our improved machine consisting of the cabinet and parts contained therein, the structure being shown partly in elevation and partly in section.

Figure 2 is a view of the machine, showing the same as partly in side elevation and partly in section, the X-ray tube drum being shown as occupying one of its predetermined normal positions.

Figure 3 is a substantially central fragmentary vertical section through the tube drum and parts immediately adjacent the same, the tube drum here occupying a position different from that shown for it in Figure 2.

Figure 4 is a substantially central fragmentary vertical section through the upper portion of the cabinet, and shows the mechanism for enabling the operator to shift the tube drum to different levels relatively to the cabinet.

Figure 5 is a side elevation of the cabinet, showing the portion thereof opposite the one shown in Figure 2.

Figure 6 is a substantially central longitudinal section through a portion of the tube drum, and shows the manner in which the X-ray tube and certain parts immediately associated therewith are detachably mounted in position.

Figure 7 is a fragmentary section through the X-ray tube and parts immediately associated therewith and is taken upon the line 7—7 of Figure 6, looking in the direction indicated by the arrows.

The cabinet appears at 7, and has generally the form of a box. It is provided with an inclined wall 8, and with a top 9, the latter having an inclined portion 10.

Mounted within the cabinet is a synchronous motor 11, and connected with the latter are a pair of conductors 12 and 13.

Disposed upon opposite sides of the motor 11 are a pair of posts 14 and 15, and connected with those posts are flexible conductors 16 and 17, used for energizing the X-ray tube, the two conductors 17 being used also for supplying current to heat the filament of the X-ray tube.

The tube drum appears at 18, and has generally the form of a cylinder, which is mounted to rock relatively to the cabinet.

Carried by the tube drum 18, and extending radially thereinto, are a pair of posts 19 and 20, of the form shown more particularly in Figures 6 and 7.

The cabinet is provided with a doorway 21, and with a door 22. The synchronous motor 11 rests upon a box 23, located within the cabinet and used for containing the transformer mechanism 23a.

A pair of supporting levers are shown at 24, 25, and are mounted upon journal pins 26, the latter extending through a pair of brackets 27, located at opposite sides of the

casing, and held in position by fastenings 28.

Extending from the supporting lever 24 to the supporting lever 25 is a cross beam 29. The purpose of the cross beam is to render the supporting levers 24, 25 rigid relatively to each other, so that the two supporting levers and the cross beams 29 are thus made to serve practically as a unit.

Connected with the under side of the cross beam 29 and extending downwardly therefrom are a pair of links 30. These links are at their lower ends secured to anchorages 31 so as to support a counter weight 32. This counter weight carries a guide pin 33, extending upwardly from it through a stationary guide 34, having the form of an eye, and mounted upon a beam 35, which extends vertically, as may be understood from Figures 1 and 4.

Mounted upon the upper portion of the beam 35 is a bearing 36. Slidably mounted in this bearing is a plunger 37. This plunger is movable vertically in relation to the bearing 36, and is provided with a tongue 38 which works in a groove 39, so as to prevent the plunger from rotating relatively to the bearing, as may be understood from Figure 4.

The plunger 37 is provided with a screw hole 40, and fitting into the latter is a screw 41, which extends downwardly from and is supported by a collar 42, serving as a bearing. A hand wheel 43 is carried by the upper end of the screw 41, and is used for turning the screw.

The operator by turning the hand wheel 43 causes the screw 41 to rotate, and this causes the plunger 37 to be raised or lowered in the direction of its length. This action raises and lowers the cross beam 29, causing the supporting levers 24 and 25 to rock upon the journal pins 26, thus lowering and raising the tube drum 18.

The parts are so proportioned that the tube drum and its contents slightly overbalance the counter weight 32, so that the cross beam 29 presses lightly but firmly against the lower end of the plunger 37. Hence the operator, by turning the hand wheel 43, can shift the tube drum 18 to different levels relatively to the cabinet body.

The tube drum 18 is carried by the supporting levers 24 and 25, and is journaled upon the outer ends thereof. The tube drum may be rocked or turned, within certain limits, upon its mountings. By means of a locking lever 44, the tube drum may be locked in any position into which it is thus brought.

An X-ray tube is shown at 45, and is provided with two extending portions 46 and 47, designated respectively as the cathode stem and the anode stem, these parts being shown more particularly in Figure 6. The X-ray tube is supported by a pair of standards 48 and 49, provided with bearings 50 and 51,

having the form of stuffing boxes and each carrying a supporting ring 52 made of cork. The bearings 50 and 51 each have a form which may be more particularly understood by reference to Figure 6. Each bearing is provided with a portion 53, detachable from the standard 48 or 49, as indicated in Figure 7, and held in position by a clamping plate 54, the clamping plate being secured by fastenings 55, as shown more particularly in Figure 7.

The cathode is shown at 56 and is heated by means of a pair of conductors 57 and 58, conveniently united in a single cord or cable 59, extending through the post 19, which is of tubular form. The anode is shown at 60, and connected with it is a heat radiator 61. A conductor 62 extends through the post 20, and is electrically connected with the flexible conductor 16.

The standards 48 and 49 engage a flat board 63 made of wood, and having a form which may readily be understood from Figures 6 and 7. Another board 64, also made of wood, is disposed parallel with the board 63 and separated therefrom by a composite plate 65, made of a mixture of lead and rubber, designated in this art as a lead rubber plate. Screws 66 extend through the boards 63 and 64 and the plate 65, into the standards 48 and 49, as may be understood from Figure 6. Thus the boards 63 and 64, with the plate 65 and other parts just mentioned, constitute a small platform carrying the standards 48 and 49, as may be understood from Figures 6 and 7.

By means of bolts 67 and butterfly nuts 68, shown more particularly at the bottom of Figure 6, the platform just described is as a whole detachably mounted upon the cylindrical tube drum 18. For this purpose the tube drum is provided with an opening 69, so that the platform, when secured in position as indicated at the bottom of Figure 6, practically closes this opening. Thus with the various movable parts just described occupying the positions indicated for them in Figures 6 and 7, the X-ray tube is located centrally with the cylindrical tube drum and disposed coaxially thereto, as may be understood from Figure 3.

The wall 8 of the cabinet is provided with two slots 70, 71, shown more particularly in Figure 1, and the two parts 19, 20, carried by the tube drum, extend loosely into the cabinet, through these two slots.

It is evident that by means of this arrangement the tube drum, carrying the X-ray tube and various other parts immediately associated therewith, can be rocked upon its mountings, and thus turned into various normal positions. For this purpose the conductors 16 and 17, used for energizing the tube and for heating the cathode filament, are sufficiently flexible and the posts 19 and 20 are

of sufficient length to allow the tube drum considerable freedom of movement.

The operator, by turning the butterfly nuts 68, can detach the platform carrying the standards 48 and 49 and the X-ray tube, these parts being for this purpose treated as a unit. The platform being detached, the operator can next inspect, remove or replace the X-ray tube, or make minor repairs thereupon.

The outer or superficial layer of the tube drum is of phenol condensation product, hard rubber or the like, and encloses a wall 72 of lead and a lining 73 of iron or steel. The tube drum as a whole is provided with an opening 74, and carries a projection 75, having a window 76 made of leather and held in position by a clamping ring 77. Ordinarily when the X-ray tube is in active use the X-rays are unable to pass out of the tube drum, except through the projection 75. Therefore in practice the tube drum is turned by hand so as to bring the projection to the proper position for the passage of the X-rays for the particular purpose contemplated. The device as here arranged is well adapted for dental work, but equally suitable for work upon the face, neck or head of the patient, or upon any other part of the patient's body.

The tube drum is provided with a doorway 78, and with a door 79 for closing this doorway, the door 79 being of arcuate form in cross section, as indicated in Figure 3. A spring 80 exerts pressure upon the door, and tends to keep the same closed. The operator by swinging the door 79 upwardly can obtain access to the interior of the tube drum.

The tube drum carries a pair of stop hooks 81 and 82, mounted upon it by means of a pin 83, as indicated more particularly in Figure 5. The two stop hooks 81 and 82 are so arranged that they limit the travel of the tube drum, by lodging against the adjacent supporting lever 25, as may be understood from the figure just mentioned.

Mounted upon the top of the cabinet is an electric switch 84, for enabling the operator to control the electrical mechanism contained within the cabinet and connected with the X-ray tube.

The tube drum may be rocked by hand into an infinite number of different angular positions within the limits of travel permitted by the stop hooks 81 and 82, so that the projecting portion 75, through which the X-rays can pass out freely, can be brought to practically any suitable position required for X-ray work.

We find that with the parts constructed and arranged as shown in the drawing and above described, the work of the motor in driving the rectifying switch does not cause the cabinet to tremble to any appreciable extent. We also find that the apparatus as a whole is easily moved around and handled in various

ways, and that the operator and any bystanders grouped around the unit are not exposed to danger either from the X-rays or from high tension shocks.

5 By the use of our device the X-rays may be so employed as to render the doses of adequate depth, and without producing burns of the skin. The X-ray tube does not become overheated to the extent of becoming dangerous, and the output of useful X-rays is very high.

10 It will be noted that the X-ray drum is provided with a single opening through which the X-rays pass out, and that this opening is adapted for use with apertures of different sizes, upon different parts of the neck or face, or other portion of the body of the patient.

15 We do not consider it necessary to explain 20 the various therapeutic and radiographic uses to which the X-ray tube may be put by aid of our invention, nor to explain the general steps employed in X-ray work.

25 We do not limit ourselves to the precise mechanism here shown and described, as variations may be made therein without departing from our invention, the scope of which is commensurate with our claims.

We claim:

30 1. The combination of a cabinet body, a tube drum supported upon said cabinet body and journaled to rock relatively thereto, said tube drum being provided with a portion through which X-rays can pass out and further provided with means for preventing X-rays from passing out except through said portion, a platform detachably connected with said tube drum, standards carried by said platform and extending therefrom radially into said tube drum for the purpose 35 of supporting an X-ray tube therein, and flexible conductors supported partly by said tube drum and extending into said tube drum, for the purpose of energizing said X-ray tube therein.

40 2. A device comprising a cabinet body, a tube drum supported by said cabinet body and having the general form of a cylinder closed at its ends, said tube drum being for 45 the most part opaque to prevent the passage of X-rays from it, but provided with a portion relatively transparent for the purpose of permitting the passage of X-rays through said portion, a platform carried by said tube drum and detachable therefrom, standards carried by said platform, an X-ray tube mounted upon said standards, so that said platform, said standards and said X-ray tube may as a unit be disengaged from said tube drum by detaching said platform therefrom, and flexible conductors connected with said X-ray tube for the purpose of energizing said X-ray tube in different positions of said tube drum.

45 3. An X-ray machine comprising a cabinet

box, supporting levers journaled upon said cabinet box and extending therefrom, a tube drum carried by said supporting levers, means for supporting an X-ray tube within said tube drum, a counterweight mounted upon said supporting levers for partially balancing the weight of said tube drum and parts carried thereby, and flexible conductors connected with said cabinet box and said tube drum, for energizing said X-ray tube.
